Dodson and Roe*

Patented Dec. 12, 1922.

UNITED STATES PATENT OFFICE.

MAX KLEIN, OF NEW YORK, N. Y., ASSIGNOR TO SHAPIRO & ARONSON, INC., OF NEW YORK, N. Y., A CORPORATION OF OHIO.

SOCKET-SUSPENSION MEANS.

Application filed November 6, 1920. Serial No. 422,257.

To all whom it may concern:

Be it known that I, MAX KLEIN, a citizen of the United States, residing at New York, in the county of New York and State of New York, have invented certain new and useful Improvements in Socket-Suspension Means, of which the following is a specification.

My invention relates to electric light chandeliers in which the sockets depend from arms which radiate outwardly from the fixture body. In these kind of devices, the socket is supported by an eye bolt which is secured adjacent the end of the arm to which is attached a loop from which the socket is suspended, this form of construction having been adopted to insure the light hanging vertically regardless of whether the arm is truly horizontal or not.

My invention has for its object to provide a construction which will insure that result under all conditions irrespective of the plane of the arm, and which will be exceedingly inexpensive to manufacture and yet will be very desirable in use.

My means of accomplishing the foregoing objects may be more readily understood by having reference to the accompanying drawings which are hereunto annexed and are a part of this specification in which—

Fig. 1 is a top view of a fragmentary portion of a chandelier arm equipped with my device.

Fig. 2 is a vertical sectional view of the same part of the device a part being shown in elevation.

Fig. 3 is a similar view showing how wide a variation the device will accommodate.

Similar reference numerals refer to similar parts throughout the entire description.

As shown in the drawings, the end 1 of the arm is provided with an opening 2 adjacent the opening 2 on the upper side of the arm which obviously is not visible

from the floor. I form two walls 3 and 4 which are adapted to engage the sides of a nut 5 the lower side 6 of which is convex and fits loosely in a concave recess or depression formed around the opening 2 in the arm 1. In this opening I mount a nipple 7 which is preferably provided with a central ornamental part 8 and has threads cut upon its ends 9 and 10, the end 9 being screwed into the nut 5 while the other end 10 is adapted to be screwed into the socket (not shown).

It will be apparent to those skilled in the art that since the nipple 7 is loosely mounted in the opening 2, that the convex nut 5 will permit it to swing to keep its center line vertical, regardless of the inclination from the horizontal by the arms on the fixture, the extent of movement being shown approximately in Fig. 3 and that the application of the weight of the socket and other parts will cause it to swing in true vertical alignment.

Having described my invention what I regard as new and desire to secure by Letters Patent is:

In a suspension device for electric fixture, a chandelier arm having an opening in its bottom wall adjacent its outer end, there being an annular recess in the said wall surrounding the said opening, the inner surface of said recess being concave, a nut, the lower side of which is fitted to and coincides with the concave surface of the annular recess, said nut having flat sides on its upper part, a threaded member screwed into the said nut, walls cast on the chandelier arm adjacent the opening, which engage the flat-sided portion of said nut, and prevents its rotation.

In testimony whereof, I have signed the foregoing specification.

MAX KLEIN.
